UNITED STATES PATENT OFFICE.

LOUIS J. FLINT, OF SOUTH WHITLEY, INDIANA, ASSIGNEE TO GRIP NUT COMPANY, A CORPORATION.

ELECTRIC DISTRIBUTER.

1,110,676.

Specification of Letters Patent. Patented Sept. 15, 1914.

Application filed January 10, 1912. Serial No. 370,470.

To all whom it may concern:

Be it known that I, LOUIS J. FLINT, a citizen of the United States, residing at South Whitley, in the county of Whitley and State of Indiana, have invented a certain new and useful Improvement in Electric Distributers, of which the following is a full, clear, concise, and exact description, reference being had to the accompanying drawings, forming a part of this specification.

My invention relates to an improvement in electric distributers, and has as its principal object the provision of a device of this character which shall be more simple and compact than those heretofore made.

A further object is to reduce the cost of manufacture of such devices.

A further object resides in the particular arrangement and combination of parts hereinafter described.

The particular devices shown, described and claimed herein are shown and described but not claimed in my co-pending applications Serial No. 581,915, filed September 13, 1910, and Serial No. 627,646, filed May 17, 1911.

In the accompanying drawings Figure 1 is a vertical longitudinal section showing my improved distributer as actually mounted in connection with a magneto device for electric ignition purposes, this figure being identical with Fig. 1 of application No. 581,915 above mentioned; Fig. 2 is a cross section on line *c-c* of Fig. 1; Fig. 3 is a vertical, longitudinal section of a second form of my device also shown as mounted in connection with a magneto and interrupter, this figure being taken from Fig. 1 of my application No. 627,646; Fig. 4 is a cross section on line *4-4* of Fig. 3; and Fig. 5 is a perspective view showing the method of assembling the conducting elements of the form shown in Figs. 3 and 4.

Referring more particularly to the drawings, 1 is a metal rod forming the center of a revolving structure which is the movable element of my distributer. Surrounding the rod 1 is an insulating sleeve 2. Surrounding the sleeve 2 in turn is a metal sleeve 3. Surrounding the sleeve 3 is a second layer of insulating material forming a bushing 4, on the outside of which is a second metal sleeve or cylinder 5. At the right of the rod 1 and the sleeve 3 is mounted a disk

or plate 6. Further to the right of the plate 6 is a similar plate 7. Mounted between these plates 6 and 7 is the armature 8 of the magneto. The plate 7 connects with a shaft 9 which is provided with suitable ball bearings and is driven from a shaft 10 by gears as shown. At the left of the revolving structure is a bearing 11, while at the left end of the shaft is the revolving part of the interrupter 12. To the left of the interrupter 12 is a stationary cap 13 within which is mounted a condenser 14. The magneto generator, the driving mechanism, the interrupter and the condenser form no part of this invention and will not be further described. The revolving elements are all mounted upon a brass box 15 of square cross section which is suitably mounted upon a base member 16. At the left end of the box 15 is a perforated iron member 17 which closes the end of the box proper and within which the bearing 11 is mounted. Suitable permanent magnets for exciting the armature are mounted upon the exterior of the box 15, but as they have nothing to do with the invention claimed herein, are not further described.

Mounted upon the central longitudinal line of the box 15 is a body of insulating material 18 which is fastened to the box by a screw 19 and to the member 17 by a second screw 20. The insulating material 18 projects through apertures in the top of the box 15 as shown at 21. The projections 21 are reduced and provided with additional projections 22. Mounted within the insulation 18 are metallic sleeves 23 having sockets for the reception of the conductors 24 which lead to the separate explosion cylinders. Sleeves 23 also are provided with pins 25 projecting through apertures in the parts 21 and 22. The cylinder 5 is provided with a series of projecting arms 26, one for each of the pins 25 and as the sleeve revolves these arms are brought into contact with the pins 25 for the purpose of producing a spark in the proper cylinder. Mounted on the ends of the bushing 4 are two insulating disks 27 which protect the cylinder 5 from the dirt and oil which might work its way along from the bearings.

It will be understood that one end of the high tension winding of the armature is connected to the cylinder 5 and that the other end of the high tension winding is

connected to earth so that when contact is made between one of the arms 26 and one of the pins 25, a spark will pass from the spark plug to the middle of the cylinder. It will be observed that my improved distributor is entirely incased and completely protected from dirt and dampness. In the form shown in Figs. 1 and 2 the complete device has a rectangular outline but this, of course, is not essential.

Referring more particularly to Figs. 3 and 4, it will be observed that the same general combination of driving means, armature, distributor and interrupter mounted to revolve together is there shown as was shown in Figs. 1 and 2. The construction of the distributor is, however, specifically different. In this form we have an interior rod 50 mounted in the center of the rotating element, an insulating sleeve 51 surrounding the rod 50, and a metal sleeve 52 outside of the insulating sleeve 51. Surrounding the metal sleeve 52, however, is a body of insulating material 53, which is cast in one piece and is provided with circular ridges as 54, as well as with oil shields 55 all cast integral. The revolving contact points are shown at 56 in Figs. 4 and 5, and are formed as projections on rings 57, the rings 57 being embedded in the ridges 54. As indicated, however, in Fig. 5, the rings 57 are made separate from the remainder of the device and are provided with apertures 58. In manufacturing the revolving element the pin or rod 59 is placed in the mold. The rings 57 are then threaded on to this rod by means of the apertures 58. As shown in Fig. 5 the apertures 58 are placed in different positions on the different rings, so that the projections 56 shall be spaced the proper angular distances from one another as required by the number of cylinders in the engine. The insulating material 53 is then cast around the rings fixing them solidly in place. As indicated by the dotted lines in Fig. 4, the ridges 54 have a continuous circular outline and the projections 56 come flush with the surface of the ridges. The stationary parts of the device shown in Fig. 3 are also somewhat different from those shown in Fig. 1. In Fig. 3 the box or casing 15 is provided with a series of apertures, as in Fig. 1. In Fig. 3, however, we have a series of separate insulating plugs 60 which project from the exterior into the interior of the casing, there being a threaded connection between the plugs and the casing, as indicated at 61. Within the plug 60 are mounted conducting sleeves 62 provided with sockets for receiving conductors which shall lead to the engine cylinders. The lower portions of the sleeves 62 are provided with pins 63 upon which are loosely mounted conducting caps 64. The caps 64 rest on the surface of the ridges 54, in order to make contact with the

projections 56 at proper intervals, the plugs 60 having extensions 65 within which the caps 64 are mounted.

It will be understood that one end of the high tension winding of the armature is connected to the rod 59 or to one of the rings 57, the other end being earthed.

Having thus described my invention, what I claim is:

1. In a distributing device, a rotary structure comprising in combination a central conducting shaft, an insulating sleeve surrounding said shaft, a metallic envelop surrounding said sleeve, a body of insulating material surrounding said envelop, and distributing fingers spaced longitudinally of said shaft supported by said material. 75 80

2. In a distributing device, a rotary structure comprising a central conducting shaft, an insulating sleeve surrounding said shaft, 85 a metallic envelop surrounding said sleeve, an integral body of insulating material surrounding said envelop, said material having embedded therein a plurality of distinct rings and a rod threaded through all of said 90 rings.

3. In a device of the class described in combination, a revolving element comprising a body of insulating material, a rod carried within said material, and a series of rings 95 each provided with projecting pieces mounted on said rod, said projections being flush with the surface of said material.

4. In a device of the class described in combination, a casing provided with a series 100 of apertures, contact points mounted in said apertures, a revolving element provided with a set of revolving contacts, and sleeves slidably mounted on said stationary contact points for coöperating with said revolving 105 contacts.

5. In a device of the class described in combination, a metallic case provided with apertures therein, a revolving element provided with contact points mounted in said 110 case, separate insulating plugs mounted in said apertures, and conducting sleeves provided with contact points mounted in said plugs. 115

6. In a device of the class described in combination, rotating means and a distributing device carried on said rotating means, said device comprising a plurality of separate arms carried at different positions longitudinally of said means and having an angular variation in position, said arms being 120 embedded in insulating material. 125

7. In a device of the class described in combination, a casing, a plurality of threaded inlets passing through said casing, insulating blocks mounted in said inlets, contact sockets carried in said blocks and movable points coöperating with said sockets. 125

8. In a device of the class described in combination, a rotating member, insulating 130

collars carried on said rotating member, conductive distributing members within said collars, removable contact points coöperating with said collars, insulating members for carrying said points and connecting sockets coöperating with said points carried by said insulating members.

9. In a distributor in combination, a series of separate metallic rings provided with integral projections, said rings being mounted in different planes longitudinally of the device and having the projections of the separate rings in different angular positions, a rod threaded through each of said rings for fixing the angular relation of one to another, and an integral mass of insulating material in which said rods and said rings are embedded.

10. In an electrical distributor in combi-

nation, a composite core built up of metal and insulating material, an integral mass of insulating material carried by and surrounding said core, and a series of separate metallic rings embedded in said mass of insulating material, each of said rings having integral projections thereon, said mass of insulating material being formed with a series of ridges or collars of circular cross section, the surface of said ridges being flush with the edges of said projections.

In witness whereof, I hereunto subscribe my name this 21st day of December, A. D. 1911.
